UNITED STATES PATENT OFFICE.

ELI A. BASEL, OF KANSAS CITY, MISSOURI.

VALVE-OPERATING MEANS.

Application filed March 5, 1924. Serial No. 697,105.

The present invention relates to valve controlling devices for regulating the fuel supply to burners, with particular reference to the class of burners using a fluid fuel, such as oil burners, gas burners, or the like. Accordingly, I have devised an improved valve controlling mechanism, in which this regulation of the fuel supply to the burner may be carried out either manually, or automatically by means of a thermostat or other form of remote control mechanism.

One of the primary objects of the invention is to provide this type of valve with an electromagnetic form of controlling mechanism, and to combine this type of controlling mechanism with a thermostatic circuit in such a manner that the operation of the thermostatic device will correspondingly influence the electromagnetic control and effect the required operation of the valve in an efficient manner.

It is also an object of the invention to include provision whereby the operations of the electromagnetic control will also effect the starting or stopping of a suitable motor, such as commonly forms a part of oil burning apparatus.

It is also sought to devise a valve controlling mechanism of this character in which provision is made for automatically cutting off the flow of fuel to the burner in the event of the burner flame becoming extinguished, and oil overflowing therefrom, and to effect this stopping of the fuel supply independently of any of the other valve controlling elements of the device. Various improvements are also provided in the specific form of the automatic tripping and releasing mechanism by which the automatic cutting off of the fuel supply is effected.

It is a further object of the invention to provide an improved construction adapted to be enclosed compactly within a metallic housing structure to which all the electrical conduits and pipe connections may conveniently be made, so that the whole will present a slight appearance, and yet permit easy access to the interior mechanism for the purpose of inspection and repair when necessary. The invention further contemplates a controlling mechanism of the character described in which every adjustment may be conveniently made for the purpose of regulating or adjusting the operation of the control mechanism in any desired man-

ner to suit the particular conditions of the burner installation with which the valve is being used.

With these general objects in view, as well as various minor objects which will appear in the course of the detailed description, the invention will now be described by reference to the accompanying drawings illustrating one form of embodiment of the same which has been found to be both practical and efficient, after which those features deemed to be novel will be particularly set forth and claimed.

In the drawing—

Figure 1 is a front elevation of a valve controlling mechanism embodying the present invention, a portion of the housing being broken away to disclose the interior working parts;

Figure 2 is a side elevation, with the housing member shown in vertical section;

Figure 3 is an enlarged vertical sectional detail view of the valve;

Figure 4 is a horizontal section, taken on the line IV—IV of Figure 2;

Figure 5 is an enlarged sectional detail view, representing a section on the line V—V of Figure 4;

Figure 6 is a plan view, showing a thermostatic device provided with the necessary electromagnetic elements for making operative connection with the improved form of valve controlling mechanism;

Figure 7 is a section taken on the line VII—VII of Figure 6; and

Figure 8 is a diagrammatic view showing the electric circuits involved in the improved construction.

Referring now to the drawings in detail, these illustrate the improved construction as making use of a diaphragm type of valve, which is made up of two casing sections 12, 13, of substantially semi-spherical form, between which is clamped a diaphragm partition 14 of suitable flexible, resilient material, as illustrated in Figure 3. By this means, a fuel passage 16 is provided within the casing section 12 at one side of the partition 14, from which passage 16 the fuel, such as oil, is conducted to the burner (not shown) by way of a pipe connection 17. The fuel is conducted to the valve by way of a supply pipe 18 leading to a chamber 19 formed in the casing section 12 for accommodating a suitable screen member 20,

to which access may be had through a clean-out opening 21 which is sealed by means of a plug 22.

The chamber 19 communicates with the valve chamber 16 by way of a port 24, the inner end of which forms a valve seat 25 adapted for engagement by the needle valve 26, the stem 27 of which is carried centrally by the diaphragm 14, as clearly illustrated in Figure 3. Interposed between the diaphragm 14 and said valve seat is a coil spring 28 which acts to reinforce the action of the diaphragm in maintaining the valve 26 normally out of engagement with the valve seat 25, which corresponds to the full open position of the valve.

The outer end of the valve stem 27 is engaged by the inner end of a valve-operating thrust rod 30, which is screw-threaded through a bearing 31 formed centrally in the casing section 13. The outer end portion of this rod 30 has mounted thereon a finger 32 provided with a set screw 33 for adjustable clamping engagement with the rod 30, this finger 32 being adapted for manual engagement for the operation of the valve 26, and also serving as an index finger with relation to a dial 13' which is formed on the outer face of the casing section 13, and thus indicating the degree of opening of the valve. In the closing of the valve, the finger 32 is designed to engage a stop or limiting screw 34 (see Figure 1) mounted in a lug 35 on the dial 13', this screw 34 being adjusted to correspond to the proper closed position of the valve, and preventing any undue clamping pressure being exerted thereon.

On the outer end of the rod 30 is also freely journaled one end of a lever 36 provided with a suitable counterweight 37 and also connected to a chain 38 or other suitable form of remote-control connection leading to the motor of any desired type of automatic heat regulating device (not shown), or this chain may, if preferred, terminate in a manually operable element whereby the lever 36 may be simply regulated by hand, from an upper floor of the building, instead of being connected with an automatic regulator. For this form of remote-control operation, the finger 32 is adjusted and set for the minimum flame position, and then connection is made between said finger and the lever 36 by means of a loop 40 swivelled on the finger 32 and adapted to be hooked over a pin 41 which is screwed into the lever 36 adjacent to its connection with the rod 30. This forms a convenient detachable connection between the manually operable finger 32 and the remote-control lever 36, although it will be understood that, if preferred, a direct operative connection may be made between the lever 36 and the rod 30 by simply screwing the pin 41 into positive clamp-

ing engagement with said rod 30, for which provision is made as illustrated in Figure 3. An adjustable stop finger 43 is also provided for limiting the downward or valve-opening movement of the lever 36 under the action of its weight 37, this finger 43 being carried by a collar 44 provided with a clamping screw 45 for adjustably securing said collar and finger to a sleeve 46 projecting outwardly from the end of the bearing 31.

A suitable sheet metal casing 50 is provided as a housing for the valve and its operating mechanism, and divided by a horizontal partition 51 into an upper compartment 52 for the electromagnetic controlling elements, and into a lower compartment 53 to which access may be had by means of a hinged door 54 having a knob or handle 55. A removable cover 56 is provided for the top of a housing 50, to afford access to the interior of a compartment 52. An opening 57 is formed in the front of the housing 50 for exposing the dial portion 33 of the valve casing 13, and the partition 51 is formed with an opening 57 for accommodating the upper end of a valve operating lever 58 which is pivotally supported, as indicated at 59, upon a lug 60 provided on the interior of the casing 13 (see Figure 3), which is also formed with openings 61 and 62 for accommodating the movements of the upper and lower ends of the lever 58. The lower arm of the lever 58 is provided with an opening, adjacent the pivot 59, for the abutting ends of the valve stem 27 and thrust rod 30, and this portion of the lever 58 is adapted for operative engagement with one of the nuts 63 whereby the valve stem 27 is clamped to the diaphragm 14. It being understood that the valve 26 is maintained normally in open position by the action of said diaphragm and the spring 28, it will be obvious that any movement of the lower arm of the lever 58 in the direction of the diaphragm 110 will tend to move the valve into closed position against the action of the diaphragm and spring 28.

The upper end of the lever 58 projects into the compartment 52, where it terminates in a split portion carrying a stop or limiting screw 64 projecting horizontally through an opening 65 in the face of the housing 50 and provided at its outer end with a finger 66; by this means the screw 120 64 may be conveniently adjusted, and the free end of the upper arm of the lever 58 is provided with a clamping screw 67 whereby the split portion of the lever is firmly engaged with the screw 64.

A suitable supporting frame 68 is provided in the compartment 52 for carrying the electromagnetic controlling elements including a pair of electromagnets 69 and 70, the latter being designed for operating a lever 130

71 which is pivoted at 72, with the front end portion of the lever depending and terminating opposite the inner end of the screw 64 with which it is adapted for engagement 5 in the closing of the valve by the movement of the lever 58. The rear end of the lever 71 is provided with suitable counterweights 73 of a size sufficient to more than counter-balance the combined action of the dia- 10 phragm 14 and spring 28, so that whenever the lever 71 is released, as hereinafter de-scribed, the counterweights 73 will operate automatically, through the levers 71 and 58, to close the valve. The extreme rear end of 15 the lever 71 is provided with a stop or limit-ing screw 74 adapted to engage the adjacent portion of the framework 68, by regulation of which screw it is possible to vary the amplitude of pivotal movement of the lever 20 71 and hence the extent of movement im-parted to the lever 58 and, correspondingly, the degree of closing movement of the valve 26. The lever 71 is latched in its raised or inoperative position, by means of a pair 25 of toggle links 75 connected respectively to the rear arm of said lever and the frame-work 68, while the joint 76 between said links 75 is connected by means of a tension spring 77 to an armature member 78 pivoted 30 to the frame work 68 in position for acting as an armature member for the rear electro-magnet 69 (see Figure 2). The function de-signed to be performed by the electromagnet 69 is to operate the armature 78, and thereby, 35 through a pull upon the spring 77, to break the toggle joint formed by the links 75, and thus unlatch and release the lever 71 to the action of the counterweights 73 for effect-ing the valve-closing movement of the lever 40 58. The function designed to be performed by the electromagnet 70 is to raise the lever 71 into valve-opening position, through the straightening of the toggle links 75, the lower link 75 being arranged and operating 45 as an armature member for said electromag-net 70. The armature member 78 and lower toggle link 75 are provided with inter-en-gaging fingers 80 and 81, respectively, so ar-ranged that the finger 80 acts to prevent any 50 rearward movement of the finger 81 or link 75 until the armature member 78 has prac-tically completed its movement under the influence of the electromagnet 69, and disen-gaged the finger 80 from finger 81, at which 55 time the tension of the spring 77 is sufficient to produce a much more abrupt breaking of the toggle joint than would be effected by a mere dragging pull upon the joint 76 exerted by an unyielding connection with the armature 78. The same action character-60 izes the operation of the electromagnet 70 and its armature link 75, which link will fully complete its movement before the spring 77 acts to withdraw the armature 65 member 78 from the other electromagnet 69.

The function of this construction is also the maintaining of the respective electromag-netic circuits closed through said armature members to the ground, until they have fully completed their respective operative move- 70 ments, as will be later explained.

Referring now to Figures 6 and 7, and the circuit diagram illustrated in Figure 8, the electromagnet 69 is connected by a conductor 84 to a switch contact 85 (see Figure 8) and also to a binding post 86 through a conductor 87, and from the post 86 a conductor 88, in which is included an electromagnet 89, leads to an adjustable contact screw 90 formed as a part of any of the usual forms of thermostats provided with the common form of thermo-responsive element 91, which is in circuit through a conductor 92 with either a battery 93 or a transformer 94 connected with an electric supply line 99. The other electromagnet 70 is provided with a conductor 95 connecting it with a switch contact 96, and also with a conductor 97 leading to a binding post 98 from which a conductor 99, in which is included an electromagnet 100, leads to the other adjustable contact screw 101 of the thermostat. As shown in Figures 6 and 7, the adjustable thermostatic contact screws 90 and 101 are carried by the usual swivelled plate 82, by which said screws may be simultaneously adjusted relative to the thermo-responsive element 91, and in the present construction this swivelled plate 82 serves also as a support for the elec-tromagnets 89 and 100, whereby these also 105 may be simultaneously adjusted with refer-ence to the armature portion provided by suitably extending the end of the element 91 in between the cores of said electromagnets. This arrangement is designed for utilizing the magnetic effect of the coils 89 and 100 for reinforcing the circuit closing movements of the element 91 and accentuating such move-ments, with a result that a more positive cir- 110 cuit closing effect is produced, using a smaller current and eliminating any ten-dency to burn the contact points.

The circuit from the thermo-responsive element 91 is completed by means of a con- 115 ductor 102 leading from either the battery 93 or the transformer 94 to a grounding post 103. The other branches of the circuit are adapted to be alternately grounded through the conductors 84 and 95 leading to the contacts 85 and 96, respectively, which are 120 adapted to be alternately engaged by contact elements 105 and 104 carried by the lower toggle link 75 and the armature 78, re-spectively, these latter being of course 125 grounded by their connection with the framework 68.

Preferably, I provide the lever 58 with a retarding device, which comprises a lever 110 pivoted to a bracket 111 within the com- 130 partment 52 (see Figure 4), a swivel connec-

tion being made between one end of the lever 110 and the split upper end portion of the lever 58. The other end of the lever 110 is pivotally connected, as indicated at 112, 5 to the central portion of a flexible diaphragm 113 carried by a concave disk 114 attached to the front wall of the compartment 52. A small air vent opening 115 is provided in the disk 114, as illustrated in Figure 5. The 10 arrangement and construction of this retarding device are such that any rearward movement of the upper end of the lever 58 is somewhat retarded by the pressure required to be exerted upon the diaphragm 113, which in turn yields only gradually as 15 air is vented out through the opening 115. This rearward movement of the upper end of the lever 58 is that which corresponds to the opening movement of the valve 26, 20 which therefore is allowed to open only gradually, as is desirable in the burning of oil fuel, in order to prevent any flooding of the burner by a too sudden increase in the supply of fuel thereto.

25 Where a liquid fuel such as oil is being supplied to the burner, a blower is often used for spraying or atomizing the fuel, in addition to supplying the necessary air to the burner, and some form of motor is required 30 for the operation of this blower. Since the operation of the blower is required only while the fuel is being fed to the burner, the automatic control of the valve should also be accompanied by a similar control for 35 the blower's operation, and accordingly in the present case I illustrate an automatic switch for starting and stopping such a motor, in agreement with the opening and closing movements of the valve. Referring to 40 Figures 4 and 8, a motor circuit 118, including a suitable motor 119, is connected with the line circuit 199, and in the circuit 118 is also included a suitable rocking switch 120, which may preferably be of the mercury- 45 tube type rocking about a pivot 121 provided in brackets 122 and 123 carried by the floor of the compartment 52. One side of the switch 120 is provided with a bell-crank 124 forming an operating arm projecting from 50 one side of the lower toggle link 75. By this arrangement it is apparent that when the toggle links 75 are straightened, to correspond with the opening of the valve 26, the mercury switch 120 is rocked slightly 55 forward with the result that the circuit 118 is closed and the motor 119 set in operation to operate the blower. Obviously, when the toggle joint 76 is broken, to release the lever 71 and permit opening of the valve 26, the switch 120 is rocked in the opposite 60 direction, for breaking the circuit 118, and stopping the motor 119.

65 The valve section 12 is formed with an oil overflow passage 126 (see Figure 3) into which is threaded one end of an oil overflow

pipe 127 leading from the burner, and also one end of an oil overflow discharge pipe 128, to the other end of which is fitted an air trap element 129 (see Figure 2). The connection of the overflow pipe 127 with the 70 valve insures the return of any overflowing oil by way of the valve, or to the position occupied by the valve, and anchors this end of the overflow pipe securely in position, instead of leaving such pipe with a free projecting end at some other point, remote from the valve, as in the usual construction.

The overflowing oil is discharged into an overflow bucket 130 located in the lower compartment 53, beneath the valve, and supported by one end of a counterweighted lever 131 the fulcrum pin 132 of which is detachably fitted in a suitable opening in another counterweighted arm 133, the forward end of which is pivoted at 134 to a lug 135 depending from the front valve section 13 (see Figure 1). The front end of the arm 133 is formed with an upwardly-projecting finger 136 designed for engagement with the lower end of the lever 58 while permitting all ordinary movements of the latter for opening and closing the valve independently of the operation of the arm 133 (see Figure 3). In the normal position of the lever 131 and of the arm 133, therefore, no operative pressure 90 is exerted by the lug or projection 136 upon the lower end of the lever 58, and the parts 131 and 133 are maintained in this inoperative position by means of a link 137 carried by an arm 138, one end of which is pivotally connected, as indicated at 139, to a projection from the rear valve section 12, while the other end of said arm 138 is supported by means of a fusible link 140 secured to the rear wall of the housing 50 adjacent to an 100 opening 142 provided for subjecting said link 140 to the influence of surrounding heat in case of fire. The lower end of the link 137 is detachably connected with a pin-like projection 144 from the lever 131, and this 110 projection 144 is preferably in direct line with the pivot pin 132 forming the connection between the lever 131 and arm 133. The construction and arrangement are such that the counterweighted portion of the lever 131 115 nicely balances the empty bucket 130, so that the weight of any oil added to the bucket will very readily disengage the projection 144 from the link 137 and thereby release both the lever 131 and arm 133, and hence 120 operate the lever 58 to close the valve by pressure of the lug 136 on the lower end of said lever 58. The same result will obviously be produced in case of a fire melting the link 140, and releasing the bucket supporting arm in the same manner.

125 The nature of the operation of the device has been indicated in a general way, but may be briefly summarized as follows. The thermostatic device operates in a manner 130

well known and understood, the thermo-responsive element 91 closing the circuit through the conductor 88 in case of a rise in temperature around the thermostat, and 5 closing the circuit to the conductor 99 in response to a fall in such temperature. Assuming a rise in temperature, the element 91 closes the circuit through the contact screw 90, which circuit closing action is reinforced 10 and accentuated by the action of the electromagnet 89 on the armature end of the element 91 which snaps tightly against the core of said electromagnet and positively closes the circuit with no opportunity for a lagging 15 action and burning of the contact points. This closing of the circuit through the conductor 88 also completes the circuit through the coil 69, the conductor 84 and contact 105 and to the ground through the lower toggle 20 link 75, as will be clear from the diagram in Figure 8, it being assumed that the initial position of the parts is that illustrated in Figure 2. The electromagnet 69 now being energized, it acts upon the armature 25 member 78 and through the spring 77 to break the toggle joint 76 and release the lever 71 to the action of its counterweights 73; as already explained, this results in the movement of the lower end of the lever 58 30 in a direction to close the valve 26 against the action of the diaphragm 14 and spring 28. This movement of the lower toggle link 75 also breaks the circuit through the electromagnet 69 by separating the contacts 85 35 and 105 (said circuit being thus maintained closed until the armature 78 has completed its operative movement), and likewise breaks the motor circuit 118 by rocking the mercury switch 120 in the same direction as the lower 40 toggle link 75. This operates to stop the blower action simultaneously with the closing of the valve. The burner will now operate with a low flame until the temperature around the thermostat has fallen sufficiently 45 to cause the element 91 to close the circuit through the conductor 99, whereupon the electromagnet 100 will operate in a similar manner as has just been explained with reference to the electromagnet 89, for positively closing the circuit at this point. This will 50 also close the circuit through the electromagnet 70 and the conductor 95 to the switch contacts 96 and 104 which, it will be recalled, were left closed by the last action of the thermostat. The electromagnet 70 now being 55 energized, it promptly attracts the lower toggle or armature link 75 and operate to straighten the toggle links and raise the lever 71 against the pull of the weights 73, 60 and thereby relatching said lever 71 in the initial position illustrated in Figure 2. This also breaks the circuit through the contact 104 and armature 78 to the ground, and recloses it through the contact elements 85 and 65 105. This movement of the lever 71 causes

its front end to back up from the screw 64, thus allowing the lever 58 to be returned to initial position by the action of the spring 28 and diaphragm 14, and thereby effecting the opening movement of the valve. Corresponding to this opening of the valve, the mercury switch 120 is rocked in a forward direction by the movement of the lower toggle link 75, for closing the circuit through the motor 119, and thus again starting the 70 operation of the blower. This opening movement of the valve is also retarded by the action of the device 113, as has already been explained, for preventing a too rapid flow of oil to the burner. In the event of the flame 80 at the burner becoming extinguished, and oil overflowing from the same to the bucket 130, the valve will be promptly closed by the tripping of the arm 133, as above explained, and the same result will be accomplished by 85 an undue rise in temperature around the valve, which would speedily melt the link 149 and in turn release the arm 133 and operate the valve-closing lever 58 to close the 90 valve.

It will thus be apparent that I have provided a practical and efficient construction for carrying out the desired objects of the invention, and that all of the parts of the mechanism may be conveniently closed in 95 compact form within the housing 50, to which all the connections may be quickly made at the several points which may be marked for the electrical conduits and pipe connections. It is also apparent that the 100 safety cut-off device, for closing the valve in response to the overflowing of oil from the burner, will operate independently of any of the other controlling devices; and, if desired, the manual control or regulation 105 of the valve through the operation of parts connected with the thrust rod 30, may be carried out independently of the electrical or magnetic control associated with the upper end of the valve controlling lever 58. Thus, the electromagnetic controlling mechanism may or may not be supplied with the valve, according to the conditions under which the same is to be installed, and if omitted the 110 electromagnetic control may be added later 115 if the conditions are so changed as to render it advisable.

While I have illustrated what I now regard as the preferred form of construction, I desire to be understood as reserving the 120 right to make all such changes or modifications as may fairly fall within the scope of the appended claims.

What I claim is:-

1. Valve mechanism for burners comprising, in combination with a burner fuel passage, a valve controlling the flow of fuel through said passage, a valve operating member for controlling said valve, an arm operative automatically under the pull of 130

gravity to actuate said member to close the valve, a receptacle for receiving oil overflowing from the burner, a counterbalancing arm supporting said receptacle and provided with a detachable pivot connection with said first arm, and a releasable supporting element provided with a detachable connection with said counterbalancing arm.

2. Valve mechanism for burners comprising, in combination with a burner fuel passage, a valve controlling the flow of fuel through said passage, a valve operating member for controlling said valve, an arm operative automatically under the pull of gravity to actuate said member to close the valve, a receptacle for receiving oil overflowing from the burner, a counterbalancing arm supporting said receptacle and pivotally carried by said arm, and a releasable supporting element provided with a detachable connection with said counterbalancing arm coinciding with the pivotal axis thereof.

3. Valve mechanism for burners comprising, in combination with a burner fuel passage, a valve controlling the flow of fuel through said passage, means for maintaining said valve normally in open position, a device operating automatically to close said valve, an electromagnet operative to actuate said valve-closing device into inoperative position, means for latching said valve-closing device in its inoperative position, an electromagnet provided with a movable armature having a yieldingly extensible tripping connection with said latching means, and means preventing the tripping of said latching means until said armature has completed its movement in response to the action of the corresponding electromagnet.

4. Valve mechanism for burners comprising, in combination with a burner fuel passage, a valve controlling the flow of fuel through said passage, means for maintaining said valve normally in open position, a device operating automatically to close said valve, an electromagnet having an armature operative to actuate said device into inoperative position and also latch said device in its inoperative position, an electromagnet provided with an armature operative to retract said first armature and unlatch said valve-closing device, and means preventing the retracting movement of either of said armatures until the other armature has completed its operative movement.

5. Valve mechanism for burners comprising, in combination with a burner fuel passage, a valve controlling the flow of fuel through said passage, means for maintaining said valve normally in open position, a device operating automatically to close said valve, an electromagnet having an armature operative to actuate said device into inoperative position and also latch said device in its inoperative position, an electromagnet provided with an armature operative to retract said first armature and unlatch said valve-closing device, each of said armatures being operative to control the circuit through the electromagnet of the other armature, and means for preventing the retracting movement of either of said armatures until the other armature has completed its operative movement.

In witness whereof I hereunto affix my signature.

ELI A. BASEL.
